CLAIM

The ornamental design for a bottle stand, as shown and described.

DESCRIPTION

FIG. 1 is a perspective view of a bottle stand showing my new design.

FIG. 2 is a front view thereof.

FIG. 3 is a rear view thereof.

FIG. 4 is a left side view thereof.

FIG. 5 is a right side view thereof.

FIG. 6 is a top plan view thereof; and,

FIG. 7 is a bottom plan view thereof.

As indicated in the title, the article of manufacture to which the ornamental design has been applied is a bottle stand. In each Figure, marks indicating shading within the border of the figure are to show contour and shape only.
